LOCK

Phillip W. Olson, Grand Rapids, Mich.

Application February 28, 1936, Serial No. 66,176

13 Claims.

(Cl. 70—21)

This invention relates in general to locks and has more particular reference to a padlock which has a combined key operated and combination lock.

The principal object of the invention is in the provision of combination and co-operating lock parts by which the lock may be operated either as a variable dial combination lock or as a key operated lock.

Further objects of the invention are in the provision of an improved lock which is simple and strong, durable in construction and adapted to be economically manufactured.

In the drawings which illustrate a preferred embodiment of the invention is a padlock of the movable shackle type.

Figs. 1, 2 and 3 are front, side and rear elevations respectively;

Fig. 4 is a face view of the lock mechanism with the top plate and combination discs removed;

Fig. 5 is a reverse sectional view of the underside of the lock plate;

Fig. 6 shows the interior with all combination discs in place;

Fig. 7 is an interior view showing the housing below the lock plate;

Fig. 8 is a median sectional view of the lock;

Figs. 9 and 10 are side and face views respectively of the second combination disc; and

Figs. 11 and 12 are side and face views respectively of the third combination disc.

Combination padlocks of this type are particularly adapted for use in connection with various types of closures where the ordinary or intended operation is by means of a knob and a plurality of combination discs, and an independently key-operated lock is connected thereto by a locking plate which is common to both mechanisms. The key lock may be operated by a master key.

Referring now more particularly to the drawings, the lock which is shown in closed or locked position comprises an outer casing 15, an inner housing or frame 16, a locking disc 17 mounted within the casing, movable with respect to the housing and independently operated from the combination side of the lock or by using a key from the other side, thereby having two distinct locks for operating a common locking disc.

At one side of the locking disc and mounted in a suitable bore in the casing 16 is a tumbler lock 18 operable by a key 19 inserted through a key opening 20 in the casing. The tumblers 18a of the lock are engageable with recesses 21 in the housing 16 and are withdrawn in a well known manner by the insertion of a proper key 19 so

that the lock tumbler 18 may be turned, carrying with it the lock plate 17.

The lock plate has a marginal extension 22 forming a bolt adapted to engage in a curved slot 23 at the shorter end of a shackle 24 insertable 5 through an opening in the casing 15, the other end of the shackle extending through another opening in the casing and seated in an opening 25 in the housing 16. At this end of the shackle it has a notch or groove 26 along one side engaged 10 by a locking pin 27 inserted in the housing at one side of the opening 25 to limit the movement of the shackle within the casing. This extremity of the shackle is also provided with an end opening 28 for seating one end of a spring 15 29, the other end of which engages in a recess 30 in the housing member 16 and tends to press the shackle outwardly.

The extremity of the inserted end of the shackle 24 is also engaged by one end of a release pawl 20 31 mounted on a pivot 32 intermediate its ends, the pivot being in the form of a screw inserted in a boss 33 of the housing and the other end of the pawl having a cam 34 and a recess 35. A spring 36 is coiled about the pivot and engages 25 the pawl to press it against the end of the shackle and when the shackle is raised the spring presses the pawl outwardly until the opposite end engages a stud 37 carried by the lock plate 17 to limit outward movement of the pawl.

This stud 37 is also adapted to engage in the recess 35 when the lock plate 17 is turned to release the shackle 24, thereby locking the lock plate against reverse movement until the shackle is closed to a position where it comes in contact 35 with the release pawl 31. The lock plate and its bolt 22 are drawn to locking position by a coil spring 39, one end of which engages a projection 40 struck out of the edge of the plate and the other end attached to a pin 41 inserted at 40 the edge of the housing and extending through a marginal notch 42 in the plate 17 to limit the movement of the plate. By a movement to the left in Fig. 4 or counter-clockwise, the plate 17 and its bolt 22 are disengaged from the shackle, the spring 29 presses the shackle outwardly in an unlocked position, and locking stud 37 engages in the recess 35, thereby holding the locking plate against locking movement until the shackle is closed to engage the end of the release pawl 31 50 which automatically releases the plate for locking movement by the spring 39.

In the combination lock, a cover plate 43 is inserted against a shoulder at the top of the casing and the casing turned over the edge to 55

hold the plate in position in a well known manner. A graduated outer dial 44 conforming to the cover is secured to the shaft of a turntable knob 45 which moves the dial and its graduations relative 5 to a mark or zero point 43a on the cover plate. Within the casing the rotatable plug of lock tumbler 18 has an extension 46 upon which are rotatable a number of combination discs 47 and 48, and a corresponding disc 49 is secured to the 10 inner end of the shaft of the knob 45 thereby with the dial 44 holding the knob in place with respect to the cover plate 43 and locating it for operating the other combination discs 48 and 47.

These discs 47, 48 and 49 have cooperating 15 projections 50, 51 and 52, and 53 respectively, and also have corresponding notches 54, 55 and 56 which are brought to register with each other in a well known manner to form a gate when the proper combination is obtained by turning 20 the knob first to the right, lining up one disc, then to the left, lining up the second disc, then to the right again lining up the third disc. Between the discs are spacing washers 57.

Within a central recess 58 of the plate 17 and 25 surrounding the stem extension 46 is a disc 59 having an extension 59a adapted to engage in a recess 58a of the disc 17, the central portion of the disc 59 having an opening for receiving the extension 46 and having extensions 59b of the 30 opening for engaging projections 60 at the base of the extension 46 where it joins the cylinder of lock 18. Between this disc 59 and the bottom disc is a flat spring 47a to press the discs apart and to press discs 47 and 48 and washers 57 together toward the disc 49.

Mounted upon a pivot 63 projecting from lock plate 17 is a locking pawl 62 in the form of a lever having a right angled extension 64 at one end to engage in the notches in the locking discs 40 when they are in alignment and thus to connect the plate 17 for unlocking movement with the discs when rotated by the knob 44 of the lock. This locking pawl has a spring 61 around the pivot with one end secured to a post 65 at the 45 edge of the locking plate and the other end of the spring extending through an opening 66 in the end projection 64 thereby tending to press the projection into the gate formed by the notches of the lock discs. The post 65 also limits the outward movement of the pawl 62.

Secured to the locking pawl 62 near the extension 64 is a contact pin 73 which projects through an opening 74 in the plate 17 and into the path of cam 34 on the release pawl.

When the lock plate 17 is moved to the left or counterclockwise, either by the key lock or the combination knob, the locking rim bolt 22 releases the shackle which springs outwardly because of its spring 29, and the lock plate spring 39 is tensioned. Outward movement of the shackle frees the release pawl 31 which springs outwardly until it engages stud 37 carried by locking plate 17 and as the plate is rotated to opening position it rides along the side of the pawl until it becomes seated in the recess 35. This prevents the return of the plate 17 by means of its spring 39 until the shackle is returned.

The notch 56 of the outer locking disc 49 attached to knob 45 has an inclined edge 67 so that 70 the above releasing movement of the plate 17 automatically presses the gate extension 64 out of the disc notches releasing the discs so they cannot operate plate 17 as long as the shackle is out. The disc 47 is held against movement by 75 a small ratchet pawl 68 mounted on a pivot 69

at the end of the lock pawl opposite the extension 64. The pawl 68 is pressed into engagement with teeth 72 on the inner lock disc 47 by its spring 70 when the plate 17 is moved to unlocking position as the cam 34 then engages the locking pawl pin 73 and holds the extension 64 of the pawl 62 from re-engagement with the combination disc notches. In releasing the shackle, after the combination has been set, the dial is moved counter-clockwise automatically throwing out 10 pawl extension 64 and by this same movement throwing the discs 47, 48 and 49 out of alignment, so they must be reset to again operate the lock.

A proper key 19 inserted in the lock withdraws the tumblers and turns the lock plug with 15 projections 60, thereby turning disc 59 and projections 59a thereof, engaging the recess 58a of the disc 17, and releasing the shackle 24 as before explained.

Thus the lock is operated either by the combination means controlled by the knob, or by a key. Both mechanisms relate to and depend for operation upon a common locking plate which is actuated and set for the return of the shackle. 25

When the shackle is released and moved outwardly under the action of its spring 29, the holding pin 27 engages in a groove around the shackle near its end, and the other end is free from the casing, so that it may be swung entirely around 30 about the mounted end but in this outer position only.

When the shackle is returned to the casing the mounted end engages the release pawl 31 which is rocked about its pivot disengaging its lock recess 35 from lock plate stud 37 and allowing the lock plate to snap back under the action of its spring 39. This also releases the locking pawl and its pin 73 from engagement with the cam 34 and allows its spring 61 to press the extension 40 64 against the discs and at the same time withdraws the lock pawl 68 from its disc engaging position. The parts are thus restored to position for operation by either lock means.

On the outer lock disc 49 are spaced projections 71 adapted to be engaged by the projection 64 at the end of the locking pawl 62 to exert a light pressure against this disc, to prevent it from twirling freely, and to prevent this disc from being shaken into or out of locking position.

This lock construction providing a common releasing plate which is operated both by a combination disc lock and by a key operated tumbler lock may also be incorporated in other types of locks when the function is to release a common locking bolt instead of the shackle of a padlock.

I claim:

1. A lock comprising a key operated tumbler at one side, a plurality of related combination locking elements at the other side, and a common locking member actuated by the tumbler from one side of the lock or by the adjustment of the elements at the other side thereof.

2. A lock comprising a casing and a movable locking member, a key operated locking device at one side of the casing, a knob operated combination lock at the opposite side of the casing, and a common locking member actuated by the key or the knob to release the locking member.

3. A lock comprising a key operated barrel plug having a key opening at one side, a plurality of combination lock discs mounted on the plug and a knob for actuating them at the side opposite the key opening, and a common lock

member also mounted on the plug and actuated both by the key and by the knob.

4. A lock comprising a key operated plug having an inner extension, combination lock discs on the extension and means for adjusting them, a common locking plate mounted on the extension and actuated by the plug, and means carried by the plate for engaging the discs for also actuating the plate by said adjusting means.

10 5. In a lock having combination discs a tumbler lock and a common locking plate, a spring tending to hold the plate in locking position, a spring actuated member locked by the plate, a release lever engaged by the member in its locked position, 15 and a projection carried by the plate and engaged by the lever to hold the plate against movement from an unlocked position by its spring until the spring actuated member is returned to its locked position.

20 6. A lock having a circular casing with key operated and combination disc locks at opposite sides having a common locking plate, a shackle member movable through the casing having a curved cut at one side, and the locking plate 25 having a projection with a curved rim extension to enter the cut for locking the bolt.

7. A lock having a casing with a locking plate movable therein, different lock mechanisms on opposite sides of the plate for operatively moving 30 it, and a lever on one side of the plate having means for engaging the plate in its release position to prevent the operation of the mechanism on the other side of the plate until the locking plate is returned from its release position.

35 8. A lock having a casing, a movable shackle, a locking plate for engaging and releasing the shackle, different lock mechanisms on opposite sides of the plate for moving it to release the shackle, a lever engaged by the shackle in its 40 locked position, and a projection carried by the plate engaged by the lever to hold the plate in a release position until the shackle is returned to engage the lever.

9. In a lock, a movable locking plate, different 45 locking mechanisms on opposite sides of the plate to operate it, a lock member engaged by the plate, a lever on one side of the plate engaged by the member when it is in locked position, the mechanism on the other side of the plate including a pawl having a projection extending through the plate and engaged by the lever to prevent the operation of either mechanism until the lock member is returned to locked position.

10. In a lock, a key operated and a disc combination lock mechanism having a common movable locking plate, a shackle movable in the lock having one end engaged by the plate, a lever engaged by the other end of the shackle in closed position and having a cam on the lever, and a release pawl pivoted to the plate engaged by the said discs and having a projection extending through the plate and engaged by said cam when the plate is moved to release the shackle thereby 10 throwing out the release pawl from engagement with the combination discs.

11. A structure in accordance with claim 10 in which the release pawl has a projection at one end and the discs have notches movable into 15 alignment to seat the projection, and a spring pressed pawl at the other end of the release pawl movable to engage one of the discs to hold it against rotation when the release pawl is disengaged at its other end.

12. A key operated and disc combination lock mechanism having a common spring pressed locking plate, a shackle engaged by the plate and a lever engaged by the shackle in its locked position, the lever having an engaging notch and 25 a cam on the end away from the shackle, a projection on the plate to engage the said notch to prevent reverse movement of the plate, a release pawl pivoted on the plate having a projection to engage the combination discs and having a pin 30 extending through an opening in the plate in the path of the cam to move the release pawl out of position to engage the discs when the plate is moved to release the shackle, and the lever engaged by the shackle releasing the lever from engagement with said projection allowing the 35 spring to return the plate and restoring both lock mechanisms to operative position.

13. A key operated and disc combination padlock having a circular casing and a shackle mounted therein for endwise movement to release one end thereof and the other end having an end groove allowing it to rotate only in outermost position, a circular cut in the short side of the shackle, a common locking plate actuated by either lock mechanism having an edge projection to engage in said cut, a spring tending to rotate the plate to engage the shackle, and means actuated by the shackle to prevent the movement of the plate by its spring when the shackle 40 is moved out of its locked position.

PHILLIP W. OLSON.
